UNITED STATES PATENT OFFICE.

EDWARD E. BETTS, OF EVANSTON, ILLINOIS.

COMBINED STOCK AND GONDOLA CAR.

1,239,558.

Specification of Letters Patent. Patented Sept. 11, 1917.

Application filed July 26, 1916. Serial No. 111,536.

To all whom it may concern:

Be it known that I, EDWARD E. BETTS, a citizen of the United States, resident of Evanston, county of Cook, and State of Illinois, have invented a new and useful Improvement in Combined Stock and Gondola Cars, of which the following is a specification, the principle of the invention being herein explained and the best mode in which 5 I have contemplated applying that principle, so as to distinguish it from other inventions.

My invention relates to railway cars and has for its object the provision of a car 15 which will be suitable for transporting live stock and also for transporting such merchandise or freight as is ordinarily carried in gondola cars. A further object is to make such provision as will permit an ordinary stock-car to be converted and render 20 it suitable for receiving, carrying and discharging such gondola freight.

As is well known coal is carried from the eastern or coal-producing part of the United 25 States to the western or cattle-producing part. Conversely cattle are transported from such western to such eastern part of the country. As is also well-known, stock-cars are indispensable for such cattle transportation and it is impractical to use such 30 cars for the transportation of coal by reason of the enforced semi-open nature of the sides of these cars and the expense of loading coal into and unloading same from such cars, and 35 gondola cars are hence universally used for this purpose.

As a result great numbers of empty gondola cars travel east and a similar number of empty stock-cars travel west.

40 A combination stock and gondola car would hence obviously effect a great economy as a result of a reduction of the number of cars in effecting a given amount of transportation, reduction of the number of non-paying car miles, reduction of initial investment, wear and tear, engines required, and all of the other attendant and collateral economies which would arise therefrom.

Inasmuch as all of the features of my invention relate to the car-body and are entirely independent of the running gear, illustration of and reference to the latter is omitted from the specification and drawings.

The annexed drawings and the following 55 description set forth in detail certain means embodying my invention, the disclosed

means, however, constituting but one of various mechanical forms in which the principle of the invention may be employed.

In said annexed drawings:—

60 Figure 1 represents a side elevation of one end of a car-body embodying my invention.

Fig. 2 represents a double transverse section, the left hand portion of the figure representing a section taken upon the plane indicated by line II^a—II^a in Fig. 1, and the right hand portion a section taken upon the plane indicated by line II—II in said figure.

Fig. 3 represents a transverse section of a 65 number of the side-slats of my improved car, and upon an enlarged scale.

Fig. 4 represents a transverse section of a 70 number of side slats of a modified form of my invention, also upon an enlarged scale.

The illustrated embodiment of my invention 75 comprises a car-body which in its general design is similar to that of an ordinary stock-car having slatted sides, closed ends, a roof and the usual side door openings provided with the usual side doors (the latter 80 not being shown).

Instead, however, of making the floor of one solid or unitary construction, it is provided with a multiplicity of discharge openings, 1, Fig. 2, suitable doors 2 being provided for closing these openings, and suitable devices being also provided for operating these doors, the latter dropping downwardly as in the case of bottom discharging doors of an ordinary gondola car. The 85 form of these doors and the means for operating same being old and well-known, it will not be necessary to give a detailed description thereof. Also as in the ordinary gondola car with bottom discharging doors, 90 these latter are located upon opposite sides of the vertical median longitudinal plane X—X, Fig. 2, of the car. Of course, when the car is used as a stock-car, these doors do not necessarily perform any function, but 95 when the car is loaded with coal or the like, its contents may be discharged as in the case of a gondola car.

In order to facilitate the loading of the car with coal or similar freight, I provide 100 the roof 3 with a multiplicity of charging openings 4, as shown in Fig. 2. These openings are closed by means of suitable doors 6. In the form of device shown in Fig. 2, these openings are located in the 105 middle of the roof, and the doors are hinged at their outer ends to the fixed portion of

the roof with their axes of oscillation parallel with and their inner ends when closed meeting at such above-mentioned plane. In this case, each of the outer surfaces of the 5 swinging ends of the doors has secured there-to a section 7 of the runway which is usually provided at the top of these cars. The doors when closed rest upon the car-lines 8, as will be understood.

10 By means of these openings, therefore, it will be seen that coal or similar freight may be readily loaded into the car and in the case of coal, the car may be run under a coal tipple and charged therefrom.

15 The two sides of the car are provided with the usual central longitudinal strips 9, Figs. 1 and 2, and with the usual vertically spaced slats 10, which form intermediate spaces for ventilation in the usual 20 manner. Each of the slats of the series of slats below the central strip 9 is provided with an inclined plate 11 secured to the outer surface and near the upper edge thereof by means of suitable bolts 12, as 25 shown in Fig. 3, the degree of inclination being preferably made steep substantially forty-five degrees (45°) at least. These plates extend upwardly and outwardly with reference to the above mentioned median

30 plane, and the inclined portion thereof is located opposite the intermediate space which is immediately adjacent to the upper edge of that slat to which the plate is secured. It will thus be seen that longitudinal openings 35 are formed between the slats which are in part at least bounded by inclined surfaces. Those faces of the adjacent slats which are opposite each other may, if desired, in anticipation of their wearing, be beveled as 40 shown in dotted lines in Fig. 3. In such event, the entire lower end of the space is bounded by an inclined plane.

It will be seen that by means of the above-described construction, while the required 45 air spaces are provided, the character of the surfaces bounding same is such that they will prevent any considerable amount of coal or similar freight from passing out of or becoming inadvertently discharged from 50 the car. The line of pressure of the coal being substantially forty-five degrees (45°) as indicated by the arrow in Fig. 3, it will be seen that the pressure will be directed substantially at right angles to that portion 55 of the bounding surfaces of the intermediate spaces along which the coal would have to travel when passing out through such spaces. Very little tendency, therefore, would exist for the coal to so pass out, as 60 will be readily understood.

The above-described construction of slats may be modified as shown in Fig. 4, in which the old form of slats is replaced by slats which are themselves steeply inclined.

65 The upper portion of the sides of the car

may be constructed exactly as in the case of an ordinary stock-car, suitable upper side doors 13 being provided and suitable feed racks 14 being placed in the inside, as shown in Fig. 2.

This upper part may be built in this manner inasmuch as it will be understood that when the car is used in place of a gondola it would never be loaded above the gondola line, that is, above the strips 9.

Inasmuch as the ordinary side door construction is not such as would withstand any considerable pressure from within, I prefer, when the car is used as a gondola, to board up these side openings from the 80 inside, as is customary when using an ordinary box car for transporting coal or the like. Under these conditions, therefore, it would not be necessary to provide the slats of the side doors with the inclined plates. 85 It will be obvious, however, that a side door construction could be devised which would obviate the necessity of boarding up and permit of the inclusion in its construction of these inclined plates or inclined slats. 90 In such event, the slats of the doors would perform their functions in the same manner as above described in connection with the main side slats of the car.

It will therefore appear that the above-described car embodying my invention includes all of the essential and required elements of a stock-car and of a gondola car, and may be produced by reconstructing an old stock-car or may be built as the above 100 description will indicate to those skilled in the art, from entirely new material.

Having fully described my invention, what I claim and desire to secure by Letters Patent is:—

1. A combined stock and gondola freight car, having an unobstructed interior space, the sides of the car being formed of spaced slats, the upper surface of which slats, below the gondola line, are steeply inclined upwardly and outwardly, the surface width with respect to the spaces between the slats and the angle of inclination being such as to adapt the car to the transport of coal, ore and similar freight in bulk, while, without change, permitting adequate ventilation throughout the car when the car is used for the transportation of live-stock, the car being provided with top and bottom openings and doors therefor.

2. A combined stock and freight car having a roof, floor, ends and sides, together with side doors, said sides being built of vertically spaced slats forming longitudinal openings, each of the slats below the gondola line having an upper surface inclined upwardly and outwardly with reference to the vertical longitudinal plane of the car, the openings above the gondola line being bounded by horizontal planes; the roof be-

ing provided with a multiplicity of charging openings upon opposite sides of the said plane, together with suitable doors therefor, and the floor being provided with a multiplicity of discharging openings upon opposite sides of said plane, together with suitable doors therefor.

3. A cattle car having plates attached individually to the strips thereof, and steeply inclined relatively thereto, each plate and strip forming an individual slat, as far up as the gondola line of the car, whereby escape of coarse material through the crevices as far as the gondola line is prevented and the car is usable without change as a gondola car.

4. A combined stock and freight car having a side provided with longitudinal slats vertically spaced from each other, each slat having an inclined plate secured thereto and inclined relative thereto so as to be located laterally opposite the opening immediately above such slat; the inclination of such plate being upward and outward with reference to the vertical longitudinal median plane of the car.

5. A combined stock and freight car having longitudinal slats forming permanently unobstructed openings, such slats being each provided with a plate secured thereto and inclining relatively thereto and upwardly and outwardly therefrom with reference to the vertical longitudinal median plane of the car.

35 6. A stock car having its lower and adjacent side slats provided with plates inclined thereto, said plates inclining upwardly and outwardly and extending so as to be located laterally opposite the longitudinal openings formed by said slats.

7. A combined stock and freight car having a side provided with longitudinal slats vertically spaced from each other, each slat having an inclined plate projecting above the top of the slat secured to its outer surface and extending upwardly and outwardly with reference to the vertical longitudinal median plane of the car.

8. A combined stock and freight car having a side provided with longitudinal slats vertically spaced from each other, each slat having a plate inclined thereto secured to its outer surface and extending so as to be located laterally opposite the opening immediately above said slat; the inclination of

such plate being upward and outward with reference to the vertical longitudinal median plane of the car.

9. A combined stock and freight car, having longitudinal slats forming permanently unobstructed openings, each such slat being provided with a plate secured to the outside thereof and inclining upwardly and outwardly with reference to the vertical longitudinal median plane of the car and to the

60
65
65

10. A stock-car having its lower and adjacent side-slats provided with plates secured to their outer surfaces, said plates inclining upwardly and outwardly and extending so as to be located laterally opposite the longitudinal openings formed by said slats.

11. A combined stock and freight car having a side provided with longitudinal slats vertically spaced from each other, each slat having a plate inclined to the slat secured thereto and extending from the upper edge thereof and so as to be located laterally opposite the opening immediately above such slat; the inclination of such plate being upward and outward with reference to the vertical longitudinal median plane of the car.

12. A combined stock and freight car having longitudinal slats forming permanently unobstructed openings, such slats being each provided with a plate inclined thereto and inclining upwardly and outwardly with reference to the vertical longitudinal median plane of the car, and from the upper edge of such slat.

13. A stock car having its lower and adjacent side slats provided with plates secured thereto, said plates extending upwardly and outwardly and inclining to the slat, from the upper edges of the slats, so as to be located laterally opposite the longitudinal openings formed by said slats.

14. A car usable for either stock or bulky freight transports without change, said car being provided with ventilating sides, the said sides being constructed of horizontal strips as far only as the gondola line, each of said strips being provided with a part extending upwardly and outwardly past the openings between said strip and the strip above, at a steep inclination, the bottom of the car being provided with means permitting freight discharge.

Signed by me, this 24th day of July, 1916.
EDWARD E. BETTS.
